METHOD OF HEAT-TREATING LOW TEMPERATURE TOUGH STEEL

Matter enclosed in heavy brackets **【】** appears in the original patent but forms no part of this reissue specification; matter printed in italics indicates the additions made by reissue.

BACKGROUND OF THE INVENTION

1. Field of the Invention

The present invention relates to a heat-treating method for imparting to a low carbon tough steel containing 1.5 to 10.0% by weight of Ni and 0.1 to 5.0% by weight Mn a very high toughness at low temperature, particularly at such an extremely low temperature as -196°C, the boiling point of liquid nitrogen, and an excellent workability, particularly low yield ratio at room temperature **【to a low carbon tough steel containing 1.5 to 10.0 wt.% Ni and 0.1 to 5.0 wt.% Mn】**.

2. Description of the Prior Art

It is well known that recently a 9%-Ni steel *has been developed which is widely used as a steel material for use at low temperature. This 9%-Ni steel is usually **【made】** manufactured into a finished product after having been subjected to hardening and tempering treatments, or to normalizing and tempering treatments, after a solid solution treatment. The thus treated product shows a relatively good toughness at low temperature, but **【it does not always follow that a】** satisfactory results can *not always* be obtained in case an optimum toughness, superior to the above-mentioned, is required.*

As regards **【to】** workability, no particularly excellent result could be obtained according to the experiments made by the inventors of the present invention.

Further, a 6%-Ni series low temperature tough steel has been developed by the inventors of the present invention as a low temperature tough steel which should take the place of the 9%-Ni steel **【, and】**. For this new steel U.S. Pat. No. 3,388,988 was granted. By subsequent investigations, however, it was discovered that in order to obtain an optimum toughness, a tempering treatment must be carried out under the optimum conditions of a relatively narrow range, which **【make a knotty point in the operation】** is *cumbersome from an operational point of view*. Also as regards the workability, the optimal result could *still not* **【still】** be secured with the 6%-Ni steel, as **【in】** is the case **【of】** with the 9%-Ni steel.

【Now, as seen from examples of 6%-Ni and 9%-Ni steels, in general, with】 When a usual heat treatment **【which is to be】** is carried out with 6%-Ni and 9%-Ni steels for obtaining a high toughness, the yield ratio becomes high, but a steel having a high yield ratio is **【used to be detested by a】** not favored by construction designers from the view point of safety. As is explained in the following, the present invention **【is to】** provides a heat-treating method, by which a steel having a high toughness can be obtained in **【the】** a wide **【range of a】** tempering temperature *range*, while keeping the yield ratio low by utilizing a segregation.

SUMMARY OF THE INVENTION

The present invention **【is to】** eliminates the above-mentioned defects of Ni-containing steels. Therefore,

the primary object of the present invention is to provide an excellent tough steel which **【is by far】** *has significantly improved* **【in the】** toughness *characteristics*, by causing **【an】** a Ni-containing steel to form a fine structure according to a method **【mentioned】** *explained* in the following, without causing thereby a reduction in **【a】** strength at low temperature.

The second object of the present invention is to impart an excellent workability, particularly a **【property of】** low yield ratio, to **【an】** a Ni-containing tough steel.

Another object of the present invention is to provide a tempering treatment **【of an】** for a Ni-containing steel with the optimum conditions **【of】** in a wide **【r】** range.

Still other objects of the present invention will be made manifest by the following description **【s】** with reference to the examples and accompanying drawings

The present invention, which is to attain the above mentioned objects, provides the method, wherein a hot-rolled steel plate containing 1.5 to 10.0% Ni, 0.1 to 5.0% Mn, and Si in an amount as required for making steel (preferably 0.05 to 0.4%) and further containing at least one element **【properly】** selected from the group consisting of 0.05 to 1.0% Mo (a part or the whole of Mo may be replaced by W), 0.10 to 2.0% Cu, 0.10 to 1.50% Cr, less than 0.05% sol. Al, less than 0.2% Nb, less than 0.2% V, less than 0.1% Zr, less than 0.1% Ti, less than 0.005% B, as the occasion demands and the balance being Fe and unavoidable impurities, is heated to a temperature above the Ac_3 transformation point **【and】** is then cooled with a cooling rate greater than **【a】** obtained by air cooling **【by air】** and thereafter is heated to a temperature between the Ac_1 transformation point and the Ac_3 transformation point and is then cooled (with a cooling rate greater than **【a】** obtained by air cooling **【by air】**) **【and then】** whereupon the thus treated steel plate is further subjected to a tempering treatment at a temperature below the Ac_1 transformation point **【,】**; or the hot-rolled steel material may be directly heated to and quenched from a temperature between the Ac_1 transformation point and the Ac_3 transformation point **【and then】** whereupon the thus treated steel plate is subjected to a tempering treatment at a temperature below the Ac_1 transformation point. Further, prior to the heating and cooling to and from a temperature above the Ac_3 transformation point or to and from a temperature between the Ac_1 transformation point and the Ac_3 transformation point, a solid solution treatment may be carried out.

BRIEF DESCRIPTION OF THE DRAWINGS

FIG. 1 is a diagram showing the relation between **【a】** tempering temperature and **【a】** toughness of a 6%-Ni series steel treated according to the method of the present invention, as compared with that of a 6%-Ni series steel treated according to a conventional method, i.e., quenched and tempered.

FIG. 2 is a photograph showing a structure by the observation with an electron microscope of a magnification of 4,500 of a 6%-Ni series hot-rolled steel plate as heated to 800°C. (above the Ac_3 transformation point) and cooled therefrom.

FIG. 3 is a photograph showing a structure by the observation with an electron microscope of a magnification of 4,500 of **【in the case where】** the steel of FIG. 2 **【is】** after having been further heated and sequentially

oled to and from 670°C.

FIG. 4 is a photograph showing a structure by the ob-
ervation with an electron microscope of a magnifica-
tion of 4,500 of [in the case where] the steel plate of
G. 3 [is] which has been further subjected to a tem-
pering treatment at 600°C.

FIG. 5 is a photograph showing a structure by the ob-
servation with an electron microscope of a magnifica-
tion of 4,500 of [in the case where] the steel plate of
G. 2 which is directly subjected to a tempering treat-
ment at 600°C.

FIG. 6 is a diagram showing the relation between
a] tempering and [a] toughness of a 9%-Ni series
steel treated according to the method of the present in-
vention, as compared with that of a 9%-Ni series steel
treated according to a conventional method.

FIG. 7 is a photograph showing a structure by the ob-
servation with an electron microscope of a magnifica-
tion of 4,500 of a 9%-Ni series hot-rolled steel plate as-
sembled to 800°C. and cooled therefrom.

FIG. 8 is a photograph showing a structure by the ob-
servation with an electron microscope of a magnifica-
tion of 4,500 of [in the case where] the steel plate of
G. 7 [is] after having been further heated to 670°C.
and subsequently cooled therefrom.

FIG. 9 is a photograph showing a structure by the ob-
servation with an electron microscope of a magnifica-
tion of 4,500 of [in the case where] the steel plate of
G. 8 [is] which is subjected to a tempering treat-
ment at 575°C.

FIG. 10 is a photograph showing a structure by the ob-
servation with [must be] an electron microscope
a magnification of 4,500 [in the case where] of the
steel plate of FIG. 7 which has been directly heated [to
exactly 6] to 575°C. and subsequently cooled therefrom.
FIG. 11 is a photograph showing a structure by the ob-
servation with an electron microscope of a magnifica-
tion of 4,500 [in the case where] of a 3%-Ni series
hot-rolled plate which is subjected to the heat-treat-
ment method of the present invention.

FIG. 12 is a photograph showing a structure by the ob-
servation with an electron microscope of a magnifica-
tion of 4,500 [in the case where] of a 3%-Ni series
hot-rolled steel plate which is subjected to hardening
and tempering treatments.

DESCRIPTION OF THE PREFERRED EMBODIMENT

The essential feature of the present invention resides
producing a structure consisting of a fine ferrite and
npered martensite, wherein a stable ultrafine austen-
or cementite is precipitated, by subjecting a hot-
led steel plate containing necessary elements in the
iges as above mentioned or a steel plate obtained by
hardening or air-cooling the hot-rolled steel plate, to
cial heating and cooling treatments to and from a
perature between the Ac_1 transformation point and
the Ac_3 transformation point and thereupon subjecting
the thus treated steel plate to a tempering treatment,
ich enables the steel to display an excellent tough-
is at a very low temperature.

[It was manifested by the] The investigations made
the inventors of the present invention demonstrated
t a relatively good toughness could be displayed
n at low temperature, when a tough steel containing
in a relatively great amount, as a 9%-Ni steel or a
-Ni steel, was subjected to hardening and tempering
atments. However, it was further discovered that, if

a hot-rolled steel plate having the composition as above
mentioned was subjected to a heat treatment specified
by the present invention, that is heating to a tempera-
ture within a range between the Ac_1 transformation
point and the Ac_3 transformation point and sequent
quenching or air-cooling from the said temperature,
[there could be obtained such an] excellent tough-
ness at low temperature and workability [as was never
seen at any] values were obtained which were far supe-
rior to those displayed by the conventional Ni-contain-
ing steels, such as 9%-Ni steel or 6%-Ni steel [,] .
[whereby the application of] The inventive steel
[for use] is therefore particularly suitable for use at
low temperature [was widely spread] . Further, as
such a remarkable improvement in the toughness at
low temperature as above mentioned could be obtained
without adding new alloy elements, that is, with a steel
having the composition in the same or even
[smaller] narrower ranges as the conventional 9%-Ni
steel or 6%-Ni steel, a very economical production of
an excellent tough steel for use at low temperature was
made possible.

In the process of manufacturing the steel of the pres-
ent invention, [a] melting may be carried out in any
25 well known steel-making furnace such as converter,
open-hearth furnace, electric furnace, high frequency
furnace and the like. There is no problem [in the
point] in respect of melting. A molten steel prepared
by melting in any of the said furnaces is regulated in its
30 composition by adding alloy elements as required and
is made to a hot-rolled steel plate through the steps of
ingotting, slabbing and hot-rolling. Then, the thus ob-
tained hot-rolled steel plate is heat-treated as specified
by the present invention.

35 The starting material [of] for performing the pres-
ent invention is a hot-rolled steel plate as above men-
tioned. In the present invention, the hot-rolled steel
plate may be immediately subjected to the special heat-
treatment of the present invention (a solid solution
40 treatment may be carried out prior to this special heat-
treatment) or, [as another method] in another em-
bodiment, the hot-rolled steel plate may be heated at
first to a temperature above the Ac_3 transformation
45 point but below the crystal grain coarsening tempera-
ture, with or without the solid solution treatment to be
carried out prior to this heat-treatment. In this case, it
is not desirable to heat the steel plate to a temperature
above the crystal grain coarsening temperature, be-
cause the toughness of the steel will be deteriorated
50 thereby. This heating is followed by [a] cooling rate
greater than [an] obtained by air-cooling, that is,
quenching, or by [an] air-cooling. The structure of
the steel after this treatment [becomes] is that of a
55 martensite structure or a mixed structure of martensite
and bainite (or a mixed structure of martensite, bainite
and ferrite according to circumstances).

The steel plate as hot-rolled or further subjected to
the heat-treatment to a temperature above the Ac_3
transformation point and sequent quenching or air-
cooling as above mentioned, is further successively
heated to a temperature in the range between the Ac_1
transformation point and the Ac_3 transformation point
and sequently quenched or air-cooled.

65 The essential feature of the present invention is just
this special heat-treatment, that is, a heating to a tem-
perature between the Ac_1 transformation point and the
 Ac_3 transformation point and sequent cooling from the
said temperature. By this heat-treatment a fine struc-

ture of the steel is produced, whereby the toughness as well as the workability of the steel can largely be improved without reducing the strength thereof at low temperature. That is, when the above-mentioned steel plate as hot-rolled or further subjected to the heat-treatment to a temperature above the Ac_3 transformation point and sequent quenching or air-cooling, is further successively heated to a temperature in the range between the Ac_1 transformation point and the Ac_3 transformation point, a fine austenite, enriched in C, Ni, Mn and N, present as an impurity, is precipitated or formed in an insular form at an old martensite crystal grain boundary, old austenite crystal grain boundary or ferrite subgrain boundary. [with the help of an effect of accelerating the] The precipitation or formation of the fine austenite is facilitated by the effect of accelerated diffusion caused by the presence of a great number of dislocation groups in the quenched or air-cooled structure which is a result [ed from] of the previous treatment [,]. [and this] This austenite is equilibrated with well annealed and fine ferrite having an excellent toughness, resulting in the formation of a mixed structure of [them] fine austenite and fine ferrite. In the present invention it is an indispensable condition that the mixed structure of austenite and ferrite is produced by the heating to a temperature between the Ac_1 transformation point and the Ac_3 transformation point. The most preferable range in the above-mentioned heating to a temperature between the Ac_1 transformation point is 620° to $800^\circ C$. [in the case of] if the steel [having] has the composition range as above mentioned. Through the sequent quenching or air-cooling, a mixed structure of ferrite and fine insular martensite can be obtained. The quenching or air-cooling from the above-mentioned temperature range may be carried out once or may be repeated several times. By repeating the said treatment several times the martensite structure is further refined, whereby the toughness of the refined steel is all the more improved. The medium for use in the quenching may be water, oil, mist or any other medium which [can perform] causes a compulsory cooling. There is no particular limitation in the medium to be selected.

The thus heat-treated steel plate is then tempered at a temperature below the Ac_1 transformation point, preferably in the range of 450° to $600^\circ C$. By this tempering treatment, austenite is again dispersedly precipitated or formed in a very fine form in the fine martensite islands, and there is finally produced a mixed structure of a pure ferrite which is the result of [resulted from] the advanced tempering, a tempered martensite and an extremely fine temper-formed or reverted austenite, whereby the toughness of the steel at lower temperature is largely improved, without causing [the] reduction of the strength.

However, in the case of the steel containing Ni in a small amount, for instance, less than 4.0 percent and less than 3.5 percent Mn, and the sum of Ni and Mn being less than 4.5 percent, there is found no appearance of the temper-formed or reverted austenite, but instead the precipitation of fine cementite in the above-mentioned islands of tempered martensite. The ferrite matrix is also purified, on account of the tempering being well advanced, and becomes a structure [rich in the] which also exhibits great toughness. [too].

In the following there will be briefly explained the reason [of having limited] for limiting the amounts

of the alloy elements to be contained in the steel of the present invention.

C is effective [on] for improving the hardenability and further elevating the stability of austenite at low temperature, as it is being absorbed into the austenite precipitated during the tempering treatment. However, if the C content is too [much] high, the amount of solid solution carbon in the ferrite matrix will increase, which impairs not only the toughness, but also the weldability of steel. Therefore, the C content [was] is limited to less than 0.2 percent.

Si is an element necessary for steelmaking and is usually contained in an amount of more than 0.05 percent. However, if it exceeds 0.4 percent, there [appears the] is a tendency [of the] that the toughness [being deteriorated] of the steel may deteriorate.

It is well known that Ni is a useful element for improving the toughness and strength of steel. Further, it serves to stabilize the temper-formed or reverted austenite at low temperature, as it is being absorbed into austenite during the tempering treatment. However, if too much Ni is added [too much], [it] the steel becomes expensive. Therefore, the upper limit thereof [was] is limited to 10.0 percent. On the other hand, if [it] the Ni content is less than 1.5 percent, the structure which is the object to be attained by the present invention can not be obtained. Therefore, it is necessary to provide a steel which contains Ni in an amount of at least more than 1.5 percent [,]; [and] and the preferable range is 4.5 to 9 percent.

Mn [serves to] not only improves the hardenability, but also, like Ni and N, stabilizes [a] the very fine austenite precipitated or formed during the tempering treatment and [elevated] increases the toughness and strength of the ferrite matrix. However, if [it] too much Mn is contained [too much] in the steel, it stabilizes carbide up to a considerably high temperature. Consequently, the upper limit [thereof was] for Mn is limited to 5.0 percent. Further, Mn is useful as an element which can replace Ni. Therefore, the range [of adding] for the Mn addition is to be properly decided [depending] in dependence on the Ni content. For instance, if Ni is contained in a range of 4.0 to 7.5 percent, it is [preferably] preferable to [contain] add Mn in an amount of more than 0.9 percent. But [,] in case Cu is added, the lower limit of Mn can be extended to 0.5 percent. On the other hand, in case the Ni content is less than 4.0 percent, there is a possibility of austenite being precipitated or formed, if Mn is added in a relatively large amount, that is, more than 1.0 percent. But [,] in [this] the latter case, that is, in the case of the Ni content being less than 4.0 percent, there is almost precipitated cementite, if the sum of Ni and Mn is less than 4.5 percent. Therefore, in adding Mn, the above-mentioned conditions must be taken into consideration in order to obtain the desired structure. Further, in case Ni is contained in a large amount, Mn may be added in a small amount. [At least with 0.1% Mn, the] The object of the present invention can be achieved with at least 0.1% Mn. Therefore, the lower limit of Mn [was decided to] is set at 0.1 percent.

Mo has the effect [s] of extending the optimum tempering temperature to the higher side, of refining the distributed states of temper-formed or reverted austenite grains and of promoting the diffusion of Mn, C and N. The addition of Mo is also effective to prevent temper embrittlement. For this purpose Mo must be

added in a range of 0.05 to 1.0 percent. The same effect can also be achieved, [even] when a part or the whole of Mo is replaced by W.

Cu may be added, as the occasion demands, in order to improve the corrosion resisting property and the toughness of the steel. Like Ni and Mn, also Cu is thought to be effective [on] for stabilizing the temper-formed austenite and for strengthening some of the solid solution ferrite matrix [itself] proper. For this purpose [it] Cu may be added in an amount of less than 2 percent.

Cr is added, as the occasion demands, in order to improve the strength of the steel. Further, it is useful for extending the optimum tempering temperature to the higher side. It is necessary to be added in an amount of 0.1 to 1.5 percent.

Al is necessary to fix nitrogen contained in the steel as an impurity, besides being added as a deoxidizer. Al may be replaced by at least one of other nitride-forming elements such as Be, Nb, V and Ta and the like. If the Al content is, however, too [much] high, the impact property of the steel at low temperature [of steel] is [deteriorated] impaired. Therefore, the Al [was] content is limited to 0.05 percent in the form of acid-soluble [one] Al.

Further, in the present invention at least one element selected from the group consisting of less than 0.20% V, less than 0.2% Nb, less than 0.1% Zr, less than 0.1% Ti and less than 0.005% B may be present for the purpose of [particularly] imparting [the] strength to the steel and for promoting the effect of refining crystal grains.

In the following the examples of the present invention shall be [shown] described.

¹Steels treated according to conventional methods

Remarks: Heat treatment: Q means a treatment of heating and cooling to and from a temperature above the Ac_3 transformation point; L means a treatment of heating and cooling to and from a temperature **below** the Ac_1 transformation point **between the Ac_1 transformation point and the Ac_3 transformation point**; T means a tempering treatment at a temperature below the Ac_1 transformation point; $^\circ C$ is temperature, mm is heating time (minute), WQ is quenching by water, and AC is cooling by air. Mechanical property: σ_y is Yield stress; σ_B is Tensile strength; Y.R. (σ_y/σ_B) is Yield ratio; $vE_{-196^\circ C}$ is V-notch Charpy impact test value-196°C.; Hv is Vickers hardness. Hr is heating time (hour).

EXAMPLE 1

In table 1 there are shown mechanical properties of about 6% Ni-containing steels, subjected to the heat treatment of the present invention. All the samples consist **ing** of steel plates having a prescribed thickness **respectively**, as **are** shown in table 1, **and** have been prepared according to *a* conventional melting process, ingotting, slabbing and hot-rolling.

Among them, the samples Nos. 6A and 6B are steels which contain 6% Ni and 1.7% Mn. **and are** These samples were obtained by directly subjecting a hot-rolled steel to the L-treatment (the treatment of heating and cooling to and from a temperature between the Ac_1 transformation point and the Ac_3 transformation point). The L-treatment is followed by the T-treatment (tempering at a temperature below the Ac_1 transformation point). In the case of the sample No. 6A the tempering temperature was 550°C. and in the case of the sample No. 6B 600°C. Both samples show an excellent toughness at low temperature. **respectively**.

The sample Nos. 6C to 6G are those obtained by subjecting a hot rolled steel plate to the Q-treatment at 800°C. for 1 hour (the treatment of heating to and cooling from a temperature above the Ac_3 transformation point) followed by the L-treatment at 670°C. and thereafter by the T-treatment at 500° to 650°C. respectively. The sample No. 6H is a reference steel, which was not subjected to the L-treatment. Concerning mechanical properties of each sample of No. 6C to 6G treated according to the method of the present invention, there are shown excellent values for the toughness at low temperature in spite of a variety of tempering temperature. The reference steel No. 6H shows only a value less than **a** one half of that of the sample No. 6E of the present invention, even though the sample No. 6H was subjected to the T-treatment under the same conditions as the sample No. 6E. From this comparison the above mentioned *advantages* will be easily understood. Further, by the application of the method of the present invention, the range of tempering temperature can be largely widened. In FIG. 1 there are shown the relations between the impact value and tempering temperature on steels of the above-mentioned samples Nos. 6C to 6G (shown by a O mark) as compared with steels treated according to conventional methods, in which the L-treatment was omitted (shown by a O mark). As is evidently seen from this figure, according to the treating method of the present invention,

a tempering treatment for obtaining high impact values can be carried out extending over a far wider range, as above mentioned, whereby **a** the difficulty in the producing process *to the effect* that the tempering treatment must be carried under much narrower conditions, as was heretofore *the case*, can be eliminated. Moreover, the samples Nos. 6C to 6G show a very low yield ratio respectively, which is particularly manifest in contrast to the sample 6H. It can **be**, therefore, *be* concluded from the foregoing that steels treated by the method of the present invention are superior in the workability **to** *as compared to that of conventional steels*.

The samples Nos. 6I to 6N show the results **of** *with heat-treated steels having the Mn content reduced to 1.10 percent, **being heat-treated**, **wherein** **of which** the samples Nos. 6I to 6K are those **which were** treated according to the method of the present invention, while the samples Nos. 6L to 6N are those treated according to *a* conventional method. The comparison of both groups shows clearly the **quite** *substantially* same tendency with respect to the toughness at low temperature and the workability of steel as is seen **at** *in the comparison of the samples Nos. 6C to 6G with No. 6H. The samples Nos. 6O and 6P are steels, which contain Cu, and show that the high toughness at low temperature can be obtained, even though the Mn content is reduced to about 0.5 percent, if the steel is treated according to the method of the present invention (for instance, No. 6O). **At last** **Finally**, the samples Nos. 6Q and 6R are steels, wherein Nb is added. In this case too, an excellent toughness at low temperature can be imparted to steel, if it is heat-treated according to the method of the present invention (for instance No. 6Q).**

As above mentioned, in the steels subjected to the heat treatment of the present invention the toughness at low temperature is remarkably improved and further the workability is **elevated** *increased*, as the yield stress is reduced, that is, the yield ratio is lowered, while there is seen no change in the tensile strength. Usually, in **the said** *such steels which contain* **s** *a relatively large amount of Mn, exceeding 1.0 percent and* **is further** *have, moreover, a high* **in the** *Mo content, cementite remains* **till** *up to the high temperature side* **at the time of** *during tempering*, whereby the toughness is impaired. **In this case, if** *If the tempering is therefore carried out at a high temperature in order to prevent the above-mentioned phe-*

omenon, the temper-formed austenite becomes unstable on cooling, resulting in a deterioration of the toughness. [thereby]. However, if the steel is treated according to the method of the present invention, austenite is precipitated in very fine form and dispersedly the steel and, in addition thereto, the structure is very stable, whereby an excellent toughness at low temperature can be obtained. Further, [as reasons of improving the toughness of steel there can be enumerated the following facts that] by the heat treatment of the present invention, the tempered structure becomes fine and the ferrite matrix [becomes a] is rendered pure one [as a result of the tempering thereof being well progressed. There are reasons for the improvement of the toughness of the steels.

In the following the structures of steels heat-treated according to the present invention shall be explained in reference to the attached figures (photograph). The samples and the treating methods applied correspond to the above-mentioned samples Nos. 6E and 6H. All figures show microphotographs of 4,500 magnifications. [respectively]. FIG. 2 shows a sample subjected to the following heat treatment: a heating to 0°C. for 1 hour with a sequent air cooling therefrom []. [wherein it] It is [evidently seen] clearly seen that the structure consists of martensite and partly bainite. FIG. 3 is a photograph showing a structure obtained by further subjecting the steel having the structure as shown in FIG. 2 to the L-treatment of heat-

5

wherein the Q-treated steel of FIG. 2 was directly subjected to the T-treatment at 600°C., resulting in the production of a coarsely precipitated or formed austenite.

25

EXAMPLE 2
In table 2 there are shown the heat-treating methods [of] for 9% Ni-containing hot-rolled steel plates and the mechanical properties obtained thereby, wherein the sample No. 9B is a steel treated according to a conventional method, that is, the steel is not subjected to the L-treatment. From the comparison with the sample 9A of the present invention it is clearly seen that the sample No. 9B [is] has a far lower [in the] toughness at low temperature than the sample No. 9A and also in [the] respect of workability is inferior to the latter, as is shown by a higher yield ratio. Further, from FIG. 6 [showing] which shows the relations between impact value and tempering temperature [on] of the steel [shown by the] of sample No. 9B, as compared with the steel treated according to the method of the present invention (see black triangle mark), it is seen that in the case of the reference steel (shown by a circle mark) the range of proper T-treatment, that is, the range of tempering temperature capable of obtaining high impact value is very narrow, while in the case of the steel of the present invention the said range is far wider, indicating that an excellent toughness can be obtained in the a wide range of tempering temperature.

Remarks: PQ is pressure quench

Other signs are of the same meaning as in Table 1

to 560°C. for 1 hour and a sequent water cooling. From this photograph it is clear that as a result of the treatment there is produced a structure, wherein a [ ] martensite transformed from precipitated or readily formed austenite enriched in C, Ni, Mn and N and precipitated finely in an insular form at an old martensite subgrain boundary, is equilibrated with ferrite, forming a mixed structure of them. The most important feature of the present invention lies just in producing the above-mentioned structure. When the steel having the structure as above mentioned is further subjected to the T-treatment of heating the steel to 600°C.

1 hour with a sequent water cooling, there is dispersedly precipitated or formed an ultrafine austenite in tempered martensite, as shown in FIG. 4. This will be more clearly observed, when compared with the structure of the reference sample shown in FIG. 5. [That is,] FIG. 5 thus shows a structure of the steel treated according to a conventional method,

55 The structures of steels subjected to various heat-treating methods in the present example are [as] shown by microphotograph of 4,500 magnifications in FIGS. 7 to 10. [respectively]. FIG. 7 is a microphotograph showing the structure obtained by the Q-treatment. From this photograph it is seen that the structure [of] in this case consists of a mixed structure of martensite and partly bainite. FIG. 8 shows the structure obtained by subjecting the steel having the structure shown in FIG. 7 to the L-treatment [ ], wherein [ ]. It is clearly seen that fine martensite in the insular form is precipitated or formed in the ferrite matrix. When further subjecting the sample of FIG. 8 to the T-treatment, there can be obtained a structure as shown by the photograph in FIG. 9, wherein the tempered martensite is formed in the ferrite matrix, where the tempering made progress, in said tempered martensite ultra fine austenite being precipitated or formed. For the purpose of comparison there is shown in FIG.

10 the final structure of sample No. 9B, which was not subjected to the L-treatment. From this figure it is quite evident that the temper formed or reverted austenite has a coarse structure, as compared with the structure shown in FIG. 9.

15 being attended with a **】** reduction of the strength, and can be easily produced, because the optimum tempering temperature extends over a wide range and further the steel can be used for various purposes, as the workability at normal temperature is strikingly im-

Remarks: VT_{Trs} (°C.) is V-notch Charpy 50% ductile transition temperature. Other signs are of the same meaning as FIG. 1.

EXAMPLE 3

In Table 3 there are shown mechanical properties, particularly the toughness and strength, of about 3.0% Ni-containing hot-rolled steel plates manufactured by a conventional method, as subjected to the Q-treatment and the T-treatment with or without the L-treatment.

The samples Nos. 3A and 3C and Nos. 3F and 3G are the steels treated according to the method of the present invention, including the L-treatment, while the samples Nos. 3D, 3E and 3H are those treated **】** to **】** by a conventional method, wherein the L-treatment is not included. From the comparison of both groups it is clear that the steels of the present invention are far superior in the toughness **】** to **】** as compared to that of conventional steels. **】** That is, **】** Thus, in the steels treated according to the method of the present invention there is produced a very fine tempered structure, wherein cementite is finely precipitated in islands of the tempered martensite. Further, as the tempering of the ferrite matrix **】** is made **】** makes progress and there

】 are **】** is produced pure ferrite of fine grains which does not contain cementite, a structure having an excellent toughness can be obtained. FIG. 11 is a microphotograph of 4,500 magnifications of the final structure of the sample No. 3A, from which the above-mentioned fact is **】** manifested to be true **】** apparent. FIG.

12 is also a microphotograph of the final structure of the sample No. 3D which was not treated according to the method of the present invention, showing that a coarse cementite is being extensively precipitated, which establishes **】** that the steel treated according to the method of the present invention is superior to the conventional steel.

As is above explained, **】** the steel, heat-treated according to the method of the present invention, has an excellent toughness at low temperature without

35 proved. However, the present invention is not limited to the examples above-mentioned, but may be modified variously within the scope of the objects of the present invention.

What is claimed is:

1. A heat-treating method for producing a steel having an excellent toughness at an extremely low temperature and **】** high strength and good workability, 40 from a steel consisting essentially of less than 0.20 wt. % C **】**, 0.05 to 0.40 wt. % Si, 0.10 to 5.0 wt. % Mn, 1.50 to 10.0 wt. % Ni as basic alloying component, with the balance being Fe and the usual impurities, comprising subjecting a hot-rolled steel plate having the said composition to a heat-treatment comprising heating to a temperature between the Ac_1 transformation point and the Ac_3 transformation point and a subsequent cooling from the said temperature at least at an air cooling rate and thereupon tempering the steel plate at a temperature below the Ac_1 transformation point **】** but sufficiently high so as to cause precipitation or formation of fine austenite.

2. A method according to claim 1, wherein the heat-treatment comprising the heating of the hot-rolled steel plate to a temperature between the Ac_1 transformation point and the Ac_3 transformation point and the subsequent cooling from the said temperature is carried out **】** repeatedly **】** more than one time.

3. A method according to claim 2, wherein prior to 55 said heat-treatment, said hot-rolled steel plate is subjected to a solid solution treatment.

4. A heat-treating method for producing a steel having an excellent toughness at an extremely low temperature and **】** high strength and good workability, 60 from a steel consisting essentially of less than 0.20 wt. % C, 0.05 to 0.40 wt. % Si, 0.10 to 5.0 wt. % Mn, **】** 1.50 to 10.0 wt. % Ni as basic alloying components with the balance being Fe and the usual impurities, comprising

15

ng heating a hot-rolled steel plate having the said composition to a temperature below the austenite grain coarsening temperature *but above* the Ac_3 transformation point and subsequently cooling the steel plate from the said temperature at least at an air-cooling rate, then subjecting the steel plate to a heat-treatment comprising heating the steel plate to a temperature between the Ac_1 transformation point and the Ac_3 transformation point and subsequently cooling said steel plate from the said temperature at least at an air cooling rate and hereupon tempering the steel plate at a temperature below ~~the Ac_1 transformation point but sufficiently high so as to cause precipitation or formation of fine austenite.~~

5 6. A heat-treating method according to claim 4, wherein the heat-treatment comprising the heating of the steel plate to a temperature between the Ac_1 transformation point and the Ac_3 transformation point and the subsequent cooling from the said temperature at least at an air cooling rate is carried out ~~repeatedly~~ more than one time.

16

6. A heat-treating method according to claim 4, wherein said hot-rolled steel plate is subjected to a solid solution treatment prior to heating the steel plate to a temperature below the austenite grain coarsening temperature *but above* the Ac_3 transformation point and subsequently cooling the steel plate from the said temperature.

10 7. A method as claimed in claim 1 wherein said steel further comprises at least one element selected from the group consisting of 0.05 to 1.0 wt.% Mo, 0.1 to 2.0 wt.% Cu, 0.1 to 1.50 wt.% Cr, less than 1.0 wt.% Nb, less than 1.0 wt.% V and less than 0.05 wt.% sol. ~~Al~~ and the rest being Fe and unavoidable impurities.

15 8. A method as claimed in claim 4, wherein said steel further comprises at least one element selected from the group consisting of 0.05 to 1.0 wt.% Mo, 0.1 to 2.0 wt.% Cu, 0.1 to 1.50 wt.% Cr, less than 1.0 wt.% Nb, less than 1.0 wt.% V and less than 0.05 wt.% sol. Al and the rest being Fe and unavoidable impurities.
